(57) **CLAIM**

I claim the ornamental design for a rod holder with liner, as shown and described.

DESCRIPTION

FIG. 1 is a perspective view of a rod holder with liner showing my new design;

FIG. 2 is a right-side elevation view thereof;

FIG. 3 is a left-side elevation view thereof;

FIG. 4 is a front elevation view thereof;

FIG. 5 is a rear elevation thereof;

FIG. 6 is a top plan view thereof;

FIG. 7 is a bottom plan view thereof;

FIG. 8 is an exploded view thereof;

FIG. 9 is a cross-section view of the rod holder with liner shown along line 9-9 of FIG. 6;

FIG. 10 is a perspective view thereof with a weld-on bracket and a fishing pole;

FIG. 11 is a perspective view thereof with an insulated can;

FIG. 12 is a perspective view thereof with a clamp;

FIG. 13 is a perspective view thereof with a transom bracket; and,

FIG. 14 is a perspective view of the liner only.

The broken lines depicting a fishing pole, weld-on bracket, insulated can, clamp, and transom bracket are included for the purpose of illustrating environmental structure and form no part of the claimed design.
